ATTORNEY

UNITED STATES PATENT OFFICE.

CHARLES J. GADD, OF LEBANON, PENNSYLVANIA; ANNA BYRE GADD EXECUTRIX OF
SAID CHARLES J. GADD, DECESSED.

APPARATUS FOR BURNING PULVERIZED FUEL.

1,814,740.

Specification of Letters Patent. Patented Sept. 3, 1910.

Application filed December 3, 1915, Serial No. 34,921. Renewed April 25, 1919. Serial No. 233,356.

To all whom it may concern:

Be it known that I, CHARLES J. GADD, a citizen of the United States, and a resident of Lebanon, in the county of Lebanon and State of Pennsylvania, have invented certain new and useful Improvements in Apparatus for Burning Pulverized Fuel, of which the following is a specification.

My invention relates to an improvement in apparatus for burning pulverized fuel and the object of my invention is to furnish a burner the discharge end of which can be moved to direct the flame, into a furnace for instance, in a manner and direction to achieve the best results without in any way interfering with the volume of the blast or the coal supply.

My invention is illustrated in the accompanying drawings forming part of this invention, in which similar letters of reference indicate similar parts throughout the several views, and in which—

Figure 1, is a central longitudinal sectional elevation through a coal dust burner embodying my improvements, the discharge end of the burner being shown entering the wall of an open hearth furnace;

Fig. 2, an elevation of the left hand end of Fig. 1;

Fig. 3, an elevation of the right hand end of Fig. 1;

Fig. 4, a sectional view of part of the burner showing its discharge end directed downward;

Fig. 5, a side elevation of eye belt for securing the hood to the secondary air chamber.

5 is the primary or high pressure air pipe into which air and the pulverized fuel are introduced through mechanism forming no part of this invention and not herein illustrated.

6 is the secondary or low pressure air inlet which discharges into a chamber or T 7 through the longitudinal center of which passes the primary air pipe 5. At its left hand, or forward, end the chamber 7 is closed and at its right hand, or rear, end it is open and at this end it carries peripherally a flange 8 which is in the form of a portion of a sphere. 9 is a hood forming a socket for the ball flange 8 of the chamber 7 and carrying the cylindrical discharge end 10 of the burner.

Within the chamber 7 the primary air

pipe 5 carries a ball 11 which operates in connection with a socket 12 which is carried by arms 13 which, preferably, form part of the hood casting 9.

14 is an extension of the primary air pipe 5, being carried by the hollow socket 12, which has a flared discharge end 15 in the discharge end 10 of the burner. I have found in use that this flared or trumpet shaped end of the pressure air pipe causes a rapid expansion of the powdered fuel within the discharge end 10 of the burner greatly assisting the mixing of the fuel with the secondary air at this point.

It will be observed that where it passes to through the closed end 16 of the chamber 7 the pressure air pipe 5 is extensively threaded and carries lock nuts 17—18, the former without and the latter within the head 16. These lock nuts permit the pipe 5 to be moved to the right or left as may be necessary to bring the ball 11 into close contact with its socket 12.

The hood 9 carries lugs 19 which are perforated for the passage of eye-bolts 20, Fig. 5, and the chamber 7 carries lugs 21 which are tapped to receive a tap bolt 22 which passes through the eye in the eye bolt 20. The hood 9 is held to the chamber 7 by the eye bolts 20 as shown which permits the discharge end 10 of the burner and the discharge end 14 of the pressure pipe to be moved up or down so that the flame from the burner may be directed so as to obtain the best results in the furnace.

Experience has demonstrated that there is in every furnace some one point, higher in some furnaces, lower in others, to which the flame should be directed to obtain the best results from the burner, hence the adjustment herein described.

The best position of the burner having been determined by experiment the space between the discharge end 10 and the sides of the burner opening 23 in the furnace 100 wall 24 are luted or otherwise suitably closed, for this point having been once ascertained no further adjustment of the burner will be necessary.

Slight sidewise adjustment of the burner 105 may sometimes be required and in order to provide for this the eye 25 in the eye bolt 20, through which the tap bolt 22 passes, is of somewhat greater diameter than that of the tap bolt.

Having described my invention I claim as new and desire to secure by Letters Patent:

1. In a pulverized fuel burner, in combination, two co-axial air-carrying pipes, two co-axial discharge nozzles, one for each pipe and spaced ball-and-socket jointed connections between the nozzles and the respective pipes, providing for separate control of the contents of the two pipes, as far as the end 5 of one of the nozzles.
2. In a pulverized fuel burner, in combination, two pipes adapted to carry air at different pressures and one within the other, a nozzle for each pipe, the inner nozzle being shorter than the outer nozzle, a ball-and-socket jointed connection between each pipe and its nozzle, the inner connection being supported by, and spaced from the outer connection and common means for tightening both connections in adjusted position. 15
3. In a pulverized fuel burner, in combination, an outer pipe, an inner pipe co-axial therewith, outer and inner co-axial nozzles, joint members upon the pipes and nozzles 25 coöperating to unite the outer and inner pipes to the outer and inner nozzles, respectively and tension means, acting across one of the joints for retaining its joint members in connection.
4. In a pulverized fuel burner, in combination, a pair of co-axial air-carrying pipes, a pair of co-axial nozzles for the two pipes, a ball and socket connection between each of the nozzles and its pipe, providing space for 35 air passage between the connections and between the nozzles, support for the inner nozzle and connection from the outer nozzle and connection, and exterior means for tightening the two connections, adapted to move 40 each nozzle toward its pipe.
5. In a pulverized fuel burner, in combination, a pair of co-axial pipes, one within the other, a spaced mechanically-connected pair of nozzles, one for each pipe, a universal joint connection between each nozzle and its pipe and tension members, secured to opposite sides of one of the universal joints, adapted to hold the two joints in adjusted position. 45
6. In a pulverized fuel burner, in combination, a chamber closed at one end and open at the other, a secondary air pipe discharging in the said chamber, a discharge nozzle for said chamber, a ball-and-socket jointed connection between said nozzle and said chamber, a primary air pipe entering said chamber, at its closed end, a second discharge nozzle, flared and entering the first nozzle and movable with the first discharge nozzle, and a ball-and-socket jointed connection 55 between the second discharge nozzle and primary air pipe, spaced from the first jointed connection. 60
7. In a pulverized fuel burner, in combination, a chamber closed at one end and open at the other, a secondary air pipe discharging into said chamber, a discharge nozzle for the said pipe, an adjustable ball-and-socket joint connection between said nozzle and said chamber, a primary air pipe entering 65 said chamber at its closed end, a discharge nozzle for said primary air pipe and a second ball-and-socket jointed connection uniting said primary air pipe and second nozzle and providing space between the two jointed 70 connections. 75

CHARLES J. GADD.
